(57) **CLAIM**

The ornamental design for a vest-backpack, as shown and described.

DESCRIPTION

FIG. 1 is a perspective view of a vest-backpack showing my new design in accordance with a first embodiment;

FIG. 2 is a front elevational view of the vest-backpack in accordance with the first embodiment;

FIG. 3 is a left side view of the vest-backpack in accordance with the first embodiment;

FIG. 4 is a right side view of the vest-backpack in accordance with the first embodiment;

FIG. 5 is a rear elevational view of the vest-backpack in accordance with the first embodiment;

FIG. 6 is a top elevational view of the vest-backpack in accordance with the first embodiment;

FIG. 7 is a bottom elevational view of the vest-backpack in accordance with the first embodiment;

FIG. 8 is a perspective view of the vest-backpack in accordance with a second embodiment;

FIG. 9 is a front elevational view of the vest-backpack in accordance with the second embodiment;

FIG. 10 is a left side view of the vest-backpack in accordance with the second embodiment;

FIG. 11 is a right side view of the vest-backpack in accordance with the second embodiment;

FIG. 12 is a rear elevational view of the vest-backpack in accordance with the second embodiment;

FIG. 13 is a top elevational view of the vest-backpack in accordance with the second embodiment;

FIG. 14 is a bottom elevational view of the vest pack in accordance with the second embodiment;

FIG. 15 is a perspective view of the vest-backpack in accordance with a third embodiment;

FIG. 16 is a front elevational view of the vest-backpack in accordance with the third embodiment;

FIG. 17 is a left side view of the vest-backpack in accordance with the third embodiment;

FIG. 18 is a right side view of the vest-backpack in accordance with the third embodiment;

FIG. 19 is a rear elevational view of the vest-backpack in accordance with the third embodiment;

FIG. 20 is a top elevational view of the vest-backpack in accordance with the third embodiment; and,

FIG. 21 is a bottom elevational view of the vest-backpack in accordance with the third embodiment.

The broken lines in the drawings illustrate environmental structure and form no part of the design.
